United States Patent Office

Des. 179,182
Patented Nov. 13, 1956

179,182

LAMP

John D. Bibbs, Lakewood, Ohio

Application January 25, 1956, Serial No. 39,914

Term of patent 14 years

(Cl. D48—20)

Fig. 2

Fig. 3

Fig. 1 is a perspective view of a lamp showing my new design the broken lines indicating the top end of a post being for illustrative purposes only;

Fig. 2 is a top plan view thereof; and

Fig. 3 is a bottom plan view thereof.

I claim:

The ornamental design for a lamp, as shown and described.
